(57) **CLAIM**

The ornamental design for an activity tracker band, as shown and described.

DESCRIPTION

FIG. 1 is a perspective view of the front and left side of an activity tracker band according to our new design.

FIG. 2 is a front view of the activity tracker band of FIG. 1. FIG. 3 is a rear view of the activity tracker band of FIG. 1. FIG. 4 is a top view of the activity tracker band of FIG. 1. FIG. 5 is a bottom view of the activity tracker band of FIG. 1.

FIG. 6 is a left side view of the activity tracker band of FIG. 1.

FIG. 7 is a right side view of the activity tracker band of FIG. 1.

FIG. 8 is a partial, enlarged rear perspective view of the activity tracker band of FIG. 1 showing the frame in an open position; and,

FIG. 9 is a perspective view of the activity tracker band of FIGS. 1-7 in an alternate, fastened position.

The broken line showing of the activity tracker module illustrates environment and forms no part of the claimed design.

The ornamental design of the present disclosure is a wrist band for use with an activity tracker module.

1 Claim, 7 Drawing Sheets
